UNITED STATES PATENT OFFICE

2,636,727

WINDOW OPERATOR—SCREW TYPE

Louis Toth, Stamford, Conn.

Application August 6, 1949, Serial No. 108,965

5 Claims. (Cl. 268—21)

1

This invention relates to window operating devices and is applicable to various types of windows having movable sashes, such as the sliding sashes of double hung windows and windows having tilting or projected sashes.

In accordance with the present invention, means are provided for applying the power for moving the movable window sashes by means of rotatable threaded spindles mounted in the window jambs and provided with suitable gearing for rotating the same. Connections are made from the spindles to the movable sashes. In the case of vertical slideable sashes, traveling nuts are connected to the sashes by brackets. In the case of projected or swinging windows, traveling nuts are provided which are connected to the sashes by means of pivoted operating arms or links. In both instances, means are provided for separately adjusting the operating mechanism at each side of the movable sash so as to secure proper equalization of movement and smooth action.

It is a common practice to mount a series of movable sashes one above the other in a single frame, and in such cases, while it is possible to provide a complete separate operating unit for each sash, it is frequently desirable to operate all of the sashes by a unitary operating means. In such instances, a single pair of threaded spindles may be mounted to operate the entire vertical series of sashes. In accordance with the present invention, such spindles are made in longitudinally adjustable sections so that proper adjustment may be made with respect to each sash to insure proper opening and closing thereof. Means are also preferably provided whereby any sash operating means may be disconnected so that one or more sashes may be left closed, while the remaining sashes are opened. These features may be used for operation of either sliding or swinging sashes.

In the accompanying drawings, certain preferred embodiments of the invention are shown for the purpose of illustrating the principles thereof but it will be understood that the invention may be utilized in other forms and modified in details as may be required.

In the accompanying drawings:

Figure 1 is a front elevation of a pair of double hung windows embodying one form of the invention, parts being broken away;

Figure 2 is a vertical section on the line 2—2 of Figure 1;

Figure 3 is a horizontal section on the line 3—3 of Figure 1;

Figure 4 is a horizontal section on the line 4—4 of Figure 1;

2

Figure 5 is a horizontal section on the line 5—5 of Figure 1;

Figure 6 is a vertical section of one of the end sill boxes;

Figure 7 is a diagrammatic view in transverse vertical section, showing a series of projected sashes mounted one above the other in a window opening;

Figure 8 is similar view, showing one of the sashes and the operating means therefor;

Figure 9 is a transverse section on the line 9—9 of Figure 8;

Figure 10 is a fragmentary vertical section on the line 10—10 of Figure 9; and

Figure 11 is a fragmentary vertical section showing an operating spindle with a modified form of adjustment.

Referring to the drawing in detail, and particularly to Figures 1 to 6, the windows comprise an upper sash 20 and a lower sash 22, the operating mechanism being shown as designed to raise and lower only the lower sash. Obviously, provision could be made for operating the upper sash also, or the sashes might be balanced against one another so as to be simultaneously moved in opposite directions, in a well understood manner. The sashes are mounted in frames comprising hollow metallic sills 24, lintels 26 and jambs 28 and 30, the jambs 30 being shown in this instance as combined to form a mullion 32. The operating means comprise a pair of threaded spindles 34, one at each side of the window, and means for rotating the spindles. In the construction shown, the spindles are mounted at the top in bearing brackets 36 fixed in the jambs which are reinforced where the brackets are attached by reinforcing plates 37. At the bottom, the spindles are mounted in thrust bearings 38, preferably of ball or roller type, which are mounted in gear boxes in the sills. The movable sash is provided with brackets 40 carrying nuts 42 which travel on the threaded spindles as the latter are rotated. Means are provided for separately adjusting the spindles so that the movable sash may be properly leveled up so as to travel freely in the jambs. Such means preferably permit of adjustment after the mounting of the windows so that in case of some slight distortion of the window frames, the sashes may still be so adjusted as to have the desired free travel.

In the construction shown, very simple and effective adjusting means are provided in which the threaded part of the spindle may be adjusted lengthwise with respect to the spindle base or bottom portion 44. Such adjusting means com-

prise forming the lower end of the spindle 34 and the upper end of the spindle portion 44, each as a half-round projection 46, such projections being provided with interlocking horizontal teeth 48. The two overlapping spindle end portions 46 are received in a sleeve 50, the lower end of which is threaded and engaged with threads 52 on the spindle portion 44. The sleeve holds the two spindle portions firmly locked together in any desired adjustment. When it is desired to change the adjustment, the sleeve 50 is unscrewed from the threads 52 and slid upwardly above the halved-together spindle ends, which may then be separated and the upper spindle portion moved up or down a distance of one or more of the teeth until the desired adjustment is reached. The sleeve 50 is then slid down over the halved-together spindle portions and screwed upon the thread 52, thus making the two spindle portions act as a single unit.

For rotating the threaded spindles at the two sides of the movable sash in unison, suitable gearing is provided. As illustrated, each of the spindle base portions 44 has fixed to it a bevel gear 54. Each of these gears meshes with a bevel gear 56 mounted on a shaft 58. Each shaft 58 carries at its opposite end from the gear 56, a gear 60, the two gears 60 being so spaced as to mesh with a bevel gear 62 carried on a fitting 64 having a squared head 66 adapted to be engaged by a socket in an operating handle 68 which is provided with a crank 70 or other means for rotating the same. The gears 54 and 56 are mounted in sill boxes 72 in the bottoms of which are located the thrust bearings 38 supporting the lower ends of the spindle portions 44. These boxes also carry bearings for the ends of shafts 58. At an intermediate portion of the sill, usually at the center thereof, is a gear box 74 which carries bearings 76 in which the adjacent ends of the shafts 58 are journaled. Projecting from the front of the gear box is a bearing sleeve 78 in which the fitting 64 carrying the gear 62 is rotatably mounted. The end of the sleeve 78 projects through an opening in the front of the sill, as shown at 80.

The jambs preferably incorporate the vertical boxes 84 in which the threaded spindles are mounted, such boxes preferably being provided with removable cover sections 86 which may be taken off for adjustment or lubrication of the spindles. The mullion 32 is preferably provided with a double box having a removable cover 88 which encloses the adjacent spindles of two adjoining sashes.

Referring to Figures 7 to 10, this shows the operator as applied to a projected type of window. Each of the projecting sashes 100 is pivoted at its upper end to sliding head blocks 102 by pivots 104. The blocks 102 slide in guides in the window jambs. The windows are also provided with arms 106 which are pivoted at their lower ends by fixed pivots 108 to the window jambs. At their upper ends, the arms 106 are pivoted by pivots 110 to the sashes. For projecting and retracting the sashes, operating arms or links 112 are provided which are pivoted at their outer ends by pivots 114 to brackets 116 on the sashes. At their inner ends, the links 112 are pivoted by pivots 118 to traveling nuts 120 screwing on threaded spindles 122 mounted in boxes 124 on the window jambs, the boxes 124 carrying vertical guide channels 126 in which slide guide shoes 128 are attached to the nuts 120. At the upper ends of the boxes are bearing brackets 130

in which the upper ends of the spindles are journaled. The spindles are of multiple part construction, the parts of which may be longitudinally adjusted so as to provide for adjustment of the position of the operating nuts 120 at the two sides of each of the sashes, thereby enabling the sashes to be adjusted so as to open and close truly, even though the window frame may be slightly deformed while being incorporated in the building. The spindle sections may be provided with halved-together extensions 132 provided with interlocking teeth 134 and enclosed by a threaded sleeve 136 similar to the construction of the adjustable spindle shown in Figures 1 to 6.

Where a series of sashes are mounted one above the other, as shown in Figure 7, the spindles are preferably made in sections, one section for each sash, and the several sections being 20 relatively adjustable longitudinally, as shown in Figure 8. Guides may be mounted at intervals so as to guide the several sections, one such guide being indicated at 137 in Figure 8. While of course it would be possible to provide a complete separate operating unit for each sash, it is preferable to operate all of the sashes in a vertical series from a single pair of sectional spindles. By making the sectional spindles 30 adjustable, it is possible to associate the spindle sections in such a way that each of the sashes will be opened and closed properly when the spindles are rotated. If there were no adjustment, any irregularities in manufacturing or mounting might prevent one or more of the sashes from closing tightly when the other sash is closed.

In order to enable the operating means to be disconnected from any particular sash or sashes which it may be desired to leave closed, nuts 40 of split construction may be utilized as shown in Figures 9 and 10. Such nuts are split along one side, the two split portions being secured together by threaded studs 138. To provide sufficient flexibility between the side portions of 45 the nut, slots 140 are preferably formed therein at the sides opposite to the split portions. To spread the nuts open so as to disconnect them from the spindles, separating studs 142 may be employed, the clamping studs 138 being first loosened.

Figure 11 shows an alternative arrangement for adjusting the spindle sections. In this case, the spindle sections are held together with a bolt 144 which slides in a vertical slot 146 in one of the spindle sections. The spindle sections may be drawn together or moved apart by the right and left screw 148, the right and left threaded portions of which screw into the ends of the two adjacent spindle portions.

For rotating the spindles, suitable gearing may be provided which may be the same as the bevel gear arrangement mounted in the window sill, as shown in Figures 1, 2 and 3.

While certain preferred embodiments of the invention have been illustrated and described in detail, it is to be understood that changes may be made therein and the invention embodied in other structures. It is not, therefore, the intention to limit the patent to the specific constructions illustrated, but to cover the invention broadly in whatever form its principle may be utilized.

I claim:

1. Window operating means for movable sashes comprising a threaded spindle mounted at each side of the window, nut members mounted on the

spindles and cooperative with the threads thereon, operative connections from the respective nut members to the adjacent sides of the sash, gearing mounted on the window structure for rotating the spindles in unison, each spindle comprising upper and lower portions having overlapping notched ends of cylindrical section, and a sleeve having a cylindrical bore slidably mounted on and enclosing said ends, one part of the spindle being screw threaded and said sleeve having a screw thread to engage therewith and hold the sleeve in position to lock the spindle ends in adjusted position said screw threaded part of the spindle being mounted in bearings located near each end thereof, one of said bearings being near the adjusting sleeve and overlapping ends of the spindle parts, so as to provide an adjustable spindle assembly held in accurate alignment.

2. In an operator for projected windows said window comprising frames including jambs and movable sashes in the frames, a vertically extending box connected to the window jamb, bearings therein, a rotary threaded spindle mounted in said bearings, a vertical guide mounted in said box, a nut for engagement with said spindle having a shoe mounted to slide in said guide, a link pivoted at one end to said nut and at the other end to the sash, gearing carried by the window structure for rotating said spindle, said nut being split through one side thereof, a screw engaging portions of the nut at each side of the split for drawing the halves of the nut together so as to cause the same to engage the threads on the spindle, and a second screw screwing in a portion of the nut for forcing the nut open so as to disengage the threads on the spindle.

3. In a window operator, a window frame and sashes mounted in a vertical series therein, said window frame including jambs, a rotary threaded spindle mounted adjacent to at least one of said jambs, said spindle comprising a series of screw threaded sections one for each sash, said sections being mounted in axial alignment and secured together in an axially adjustable manner by securing and adjusting means, said means comprising overlapping ends of half-round cylindrical section at the adjacent ends of the spindle sections, and a sleeve having a cylindrical bore slidably mounted on and enclosing said ends, a bearing carried by the window frame for the upper end of the upper spindle section and a bearing carried by the window frame for the lower end of the lower spindle section, intermediate bearings carried by the window jambs, there being an intermediate bearing provided for each intermediate spindle section engaging said section near the upper end thereof, a traveling nut mounted on each spindle section and adapted to travel over a threaded part of said section between the sleeve at the lower end of the section and the supporting bearing near the upper end of said section, means connecting each nut to its respective sash, and means for rotating said spindle about its axis, said adjustable connections between said sections in cooperation with said end and intermediate bearings maintaining said shaft sections in alignment against the strains of torque applied by said spindle rotating means, and thrust due to action of said sash operating connecting means on said nuts.

4. In a window operator for projected sashes, a window frame and sashes mounted in a vertical series therein, said window frame including jambs, a rotary threaded spindle mounted adjacent to at least one of said jambs, said spindle

comprising a series of screw threaded sections one for each sash, said sections being mounted in axial alignment and secured together in axially adjustable arrangement by securing and adjusting means, said means comprising overlapping notched ends of half-round cylindrical section at the adjacent ends of the spindle sections, and a sleeve having a cylindrical bore slidably mounted on and enclosing said ends, a bearing carried by the window frame for the upper end of the upper spindle section and a bearing carried by the window frame for the lower end of the lower spindle section, a series of intermediate bearings carried by the window jambs one for each intermediate spindle section engaging said section near the upper end thereof below the notched end thereof engaged by said sleeve, a traveling nut mounted on each spindle section and adapted to travel over a threaded part of said section between the sleeve at the lower end of the section and the supporting bearing near the upper end of said section, a link connecting each nut to its respective sash, means for rotating said spindle about its axis, said adjustable connections between said sections in cooperation with said end and intermediate bearings maintaining said shaft sections in alignment against the strains of torque applied by said spindle rotating means, and lateral thrust due to action of said sash operating links on said nuts, a vertical guideway carried by at least one window jamb adjacent to a spindle mounted thereon, each nut incorporating a shoe mounted to slide vertically in said guideway and assist in maintaining the alignment of said spindle sections.

5. In a window operator for projected sashes, a window frame and sashes mounted in vertical series therein, said window frame including jambs, a rotary threaded spindle mounted adjacent to at least one of said jambs, said spindle comprising a series of screw threaded sections, one for each sash, said sections being mounted in axial alignment and secured together in axially adjustable arrangement by securing and adjusting means, said means comprising overlapping notched ends of half-round cylindrical section at the adjacent ends of the spindle sections, and a sleeve having a cylindrical bore slidably mounted on and enclosing said ends, a bearing carried by the window frame for the upper end of the upper spindle section and a bearing carried by the window frame for the lower end of the lower spindle section, an intermediate bearing carried by the window jambs for each intermediate spindle section engaging said section near the upper end thereof below the notched end thereof engaged by said sleeve, a travelling nut mounted on each spindle section and adapted to travel over a threaded part of said section between the sleeve at the lower end of the section and the supporting bearing near the upper end of said section, a link connecting each nut to its respective sash, means for rotating said spindle about its axis, said adjustable connections between said sections in cooperation with said end and intermediate bearings maintaining said shaft sections in alignment against the strains of torque applied by said spindle rotating means and lateral thrust due to action of said sash operating links on said nuts, a vertical guideway carried by at least one window jamb adjacent to a spindle mounted thereon, each nut incorporating a shoe mounted to slide vertically in said guideway and assist in maintaining the alignment of said spindle sections, and means for selectively engaging or disengag-

ing each nut from threaded engagement with its spindle section.
